(57) **CLAIM**

The ornamental design for a tripart sectional helmet with planar springs, as shown.

DESCRIPTION

FIG. 1 is a perspective view of a first embodiment showing our new design for a tripart sectional helmet with planar springs;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is an underside view of the top elevation thereof. The broken lines shown in the drawings depict unclaimed environment only and form no part of the claimed design.
